REFLECTOR FOR CHRISTMAS TREES

Application filed March 16, 1931. Serial No. 522,940.

This invention relates to a reflector for decorative use and while the invention might have various applications, it particularly is designed for a Christmas tree light or similar decorative use. It has become popular to use reflectors with the well known electric lights now used for illuminating Christmas trees. It is desirable in such a reflector to have a construction which will be highly ornamental and which will reflect the light in a way to add to the appearance of the reflector and at the same time assist in the illumination of the tree. It is also necessary in a reflector, that it have some means by which the lamp and reflector will be held firmly in position in relation to the socket, so that it will be passed by the Board of Insurance Underwriters. This means must be simple in order to be commercially practicable.

It is an object of this invention, therefore, to provide a reflector of simple construction which at the same time is highly ornamental and has illuminating functions resulting from the cooperation of its various parts.

It is a further object of the invention to provide a reflector comprising a sheet of material cut in such a manner as to provide two series of projecting tongues, the tongues of one series preferably being located in a different surface or in different positions than the tongues of the other series.

It is a further object of the invention to provide a reflector such as set forth in the preceding paragraph, in which one series of tongues is provided with a multiplicity of substantially semi-spherical portions to cause bright spots or high lights by reflecting the light from the lamp used with the reflector.

It is still another object of the invention to provide a reflector made from a sheet of metal having a highly polished surface, said reflector having a central portion preferably flat and provided with a central aperture for receiving the plug portion of a lamp bulb used, said sheet being formed with a series of radially extending tongues and a second series of radially extending tongues disposed respectively between the first mentioned

tongues and of shorter length, the tongues of said last mentioned series being disposed in different positions than the tongues of the first mentioned series.

These and other objects and advantages 55 of the invention will be fully set forth in the following description made in connection with the accompanying drawing, in which like reference characters refer to similar parts throughout the several views and in 60 which:—

Fig. 1 is a view in front elevation of the reflector;

Fig. 2 is a vertical section on line 2—2 65 of Fig. 1; and

Fig. 3 is a view similar to Fig. 2, showing the reflector mounted in position in relation to the socket and bulb.

Referring to the drawing, a reflector is shown made from a sheet of material, and 70 while various materials might be used, in practice a special metal taking a high polish has been used, which metal is non-corrosive. The sheet of metal has a central portion 10, and while this central portion might have 75 various shapes, in the embodiment of the invention illustrated it is shown as substantially flat. Said central portion has an aperture 11 therein shown as circular in form, adapted to receive the plug portion 80 of a lamp bulb 18. The sheet of metal has struck up therefrom or formed therefrom, the circumferentially arranged prongs 13 which have substantially pointed ends and project forwardly from the portion 10 at 85 the edge of the opening 11. The sheet of metal is cut to form a series of outwardly extending tongues 14 which project substantially radially from the center of opening 11, said tongues 14 being shown as having 90 pointed ends. While the tongues 14 can be bent to various positions, in the embodiment of the invention illustrated they are shown as curved somewhat forwardly to have concave forward sides as clearly shown 95 in Fig. 2. Tongues 14 and the central portion 10 of the reflector have formed therein a multiplicity of quite small substantially semi-spherical portions 15, in the embodiment of the invention illustrated, these por-

100

tions being shown as depressed semi-spherical recesses. The metal of the sheet is also cut to form a second series of outwardly projecting tongues 16. These tongues 16 are disposed respectively between the tongues 14 and have pointed outer ends, the edges of which meet at a blunter angle than the outer edges on the tongues 15. The inner portions of the tongues 16 have edges 10 which diverge outwardly from their inner ends. In the embodiment of the invention illustrated, the tongues 16 have plain front surfaces which of course, are highly polished. The tongues 16 are disposed in front of 15 the tongues 14 and also curve forwardly so as to be in the surface of an angular trough disposed forwardly of the annular trough-like surfaces in which tongues 14 lie.

20 In operation the reflector is held against the front of the socket 17 as shown in Fig. 3. The lamp bulb 18 is screwed into the socket and the outwardly flaring surface 12a of the lamp bulb engages the ends of the 25 prongs 13, thus holding the reflector firmly against the front of the rib 17a on the socket 17. If a socket is used which is not provided with the rib 17a spaced from the front, the reflector will, of course, be held 30 against the front of the socket. With the parts assembled as shown in Fig. 3, the light from the filament in the bulb 12 will be reflected from the tongues 14 and the small semi-spherical portions 15 will each show 35 a bright spot or high light and this gives a jeweled effect to the portions having the depressions 15. The light from the bulb 12 will also be reflected from the tongues 14 in various directions and some of these 40 portions of the tongues 14 will be seen by reflection in the tongues 16. The light reflected from the tongue 16 will be directed in various directions, some of which will help to illuminate parts of the tree and the 45 other ornaments thereon, and some of this light will also be reflected from the tongues 14, giving a greater illumination to some of the tongues 14. The tongues 14 and 16 are quite flexible and the decorator may prefer 50 to bend some of the tongues more than others, depending upon the position the reflector has on the tree. If the reflector is in a lower portion of the tree, some of the tongues 16 at the bottom of the reflector 55 should be given a greater concavity so that light would be directed upwardly into the tree. The reverse effect would be given the reflectors adjacent the top of the tree. The combined effect of the reflection from the 60 respective tongues 14 and 16 gives a very highly decorative effect to the device.

From the above description it is seen that applicant has provided a simple and yet very effective Christmas tree reflector. The 65 same can be easily and inexpensively made

from a single sheet of metal. The parts are so arranged that not only is a very ornamental appearance given, but the parts co-operate in an illuminating effect to produce new and useful results. The device is easily held in place and entails no fire hazard. The same has been amply demonstrated in actual practice, and found to be very successful and efficient.

It will, of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A reflector for a Christmas tree or similar decorative use, comprising a sheet of material having a flat central portion with an aperture therein for receiving the plug portion of a lamp bulb, said sheet being slotted to form a plurality of radially extending tongues, and a plurality of radially extending tongues disposed respectively between said first mentioned tongues and curved forwardly out of the surface occupied by said first mentioned tongues, thus forming spaces between the front of the first mentioned tongues and said second mentioned tongues through which light may be reflected, all of said tongues extending from and being integral with said flat central portion.

2. A reflector for a Christmas tree or similar decorative use comprising a sheet of metal having a central aperture and having a series of tongues integral with and extending radially therefrom curved slightly forwardly from the plane of said aperture, and a second series of tongues integral with and extending radially therefrom of shorter length than the tongues in said first mentioned series and disposed respectively between the tongues of said first mentioned series, the tongues of said second series being curved forwardly a greater amount than the tongues of said first mentioned series.

3. A reflector for a Christmas tree or similar decorative use comprising a sheet of metal having a flat central portion with an aperture therein for receiving the plug portion of a lamp bulb and having a series of radially extending pointed tongues formed therefrom and having a second series of radially extending tongues formed therefrom of shorter length than the tongues of the first mentioned series, and having their sides diverging outwardly in concave curves at their inner portions all of said tongues merging into said flat central portion.

4. A reflector for a Christmas tree or similar decorative use comprising a sheet of

metal having a central portion in one plane with a central aperture adapted to receive the plug portion of a lamp bulb and having a series of radially extending tongues 5 formed thereon curved forwardly out of said plane at their outer ends, and a second series of radially extending tongues disposed respectively between said first mentioned tongues and curved at their outer ends to 10 positions forwardly of said first mentioned tongues, the tongues of one of said series having formed therein a multiplicity of small substantially semi-spherical portions, and the tongues of said other series having 15 plain surfaces, said reflector being highly polished.

5. A reflector for a Christmas tree or similar decorative use comprising a sheet of metal having a central portion disposed in 20 one plane with an aperture therethrough and being cut to form a series of radially extending circumferentially spaced tongues having convex side edges converging in a point at the outer end of said tongue and 25 also to form a second series of substantially radially extending circumferentially spaced tongues, the tongues of said second series each having edges which are concave at their inner portions and convex at their outer portions, said outer portions also converging to a point, one set of said tongues having 30 their outer ends disposed forwardly of the outer ends of said other set.

6. A reflector for a Christmas tree or 35 similar decorative use comprising a sheet of material having a flat central portion with an aperture therein for receiving the plug portion of a lamp bulb, said sheet being slit 40 to form a plurality of outwardly extending similar tongues of one shape and a plurality of outwardly extending similar tongues of a different shape, disposed respectively between the first mentioned tongues.

45 7. A reflector for a Christmas tree or similar decorative use comprising a plurality of similar tongues having their inner portions in a common plane, said tongues having their outer portions curved forwardly out of said plane, a plurality of similar tongues having their inner portions disposed in said plane, said latter tongues having their outer portions curved forwardly into a different plane than said first 50 mentioned tongues, and being disposed respectively between said first mentioned tongues.

LAMBERT L. RAYMOND.
